UNITED STATES PATENT OFFICE.

CHARLES H. PAEPLow, OF BUFFALO, NEW YORK.

APPARATUS FOR USE IN MAKING BELTS OR THE LIKE.

Application filed May 16, 1922. Serial No. 561,402.

To all whom it may concern:

Be it known that I, CHARLES H. PAEPLow, a citizen of the United States, residing at Buffalo, in the county of Erie and State 5 of New York, have invented a new and useful Improvement in Apparatus for Use in Making Belts or the like, of which the following is a specification.

This invention relates to improvements in 10 apparatus for use in connection with the vulcanizing of belting of the kind commonly referred to as rubber belting. Apparatus of this kind generally includes a pair of heated platens which are adapted to be 15 pressed against opposite faces of portions of a belt for the purpose of curing or vulcanizing the same, one of the platens having bars or members adapted to confine the sides of the belts to hold the same against spreading. 20 In the use of an apparatus or press of this kind a length of belt to be cured is first fed to the apparatus by pulling the same lengthwise into the desired position, and is then stretched, which causes the portion of the 25 belt which is stretched to decrease in width. Consequently the side bars or members of the apparatus must be moved toward and from the belt at each operation of the apparatus.

30 The objects of this invention are to provide an apparatus or press of this kind with means of improved construction for moving the side bars of the press toward and from the sides of the belt; also to provide mechanism of this kind which can be easily adjusted so as to adapt the apparatus to operate on belts of different widths; also to improve the construction of apparatus of this kind in other respects hereinafter specified.

40 In the accompanying drawings:

Fig. 1 is a fragmentary sectional plan view of an apparatus embodying the invention, showing a top plan of the lower platen of the apparatus.

45 Fig. 2 is a fragmentary longitudinal sectional elevation thereof on line 2—2, Fig. 1.

Fig. 3 is a fragmentary end elevation thereof.

50 Figs. 4 and 5 are fragmentary top plan views on an enlarged scale of the lower platen, showing the parts in different positions.

Fig. 6 is a fragmentary side elevation of the apparatus.

55 Fig. 7 is a fragmentary top plan view

thereof on a still larger scale showing the mechanism for moving the side bars laterally of the apparatus.

Fig. 8 is a transverse sectional elevation thereof on line 8—8, Fig. 7.

Fig. 9 is a longitudinal sectional elevation thereof on line 9—9, Fig. 8.

Fig. 10 is a perspective view of one of the links connecting the side bars and the actuating mechanism therefor.

A, Figs. 2, 3 and 6, represents the upper platen or plate of the press and B represents the lower platen or plate. These two platens are adapted to move relatively to each other to engage the opposite sides of a 50 length of belt for vulcanizing the same. In the apparatus shown in the drawings the upper platen A is stationary, being suitably secured to the base of the apparatus (not shown) by means of upright pillars or posts 75 a and the lower platen B is movable toward and from the upper platen by means of suitable mechanism (not shown) connected to the platen by means of plungers or the like b. Both of the upper and lower platens are 80 heated by any suitable means. All of these parts have heretofore been used in connection with vulcanizing presses and of themselves constitute no part of this invention. In the use of this press for curing or treat- 85

ing a belt, a length of belt is fed into the press and is then stretched, after which the lower platen B is moved upwardly to press the length of belt in the apparatus between the two platens. After the length of belt in 90 the apparatus has been treated the belt is again fed lengthwise through the press until an untreated portion of the belt comes into operative relation to the platen, whereupon the operation is repeated. While the belt is 95 under pressure between the platens it tends to spread laterally due to the pressure exerted thereon and for this purpose side bars C are provided which are adapted to engage the opposite sides of the belt to prevent the spreading of the same. The side bars must be moved out of engagement with the sides of the belt after a length of belt has been cured in order to permit an un- 100 stretched and consequently wider portion of 105 the belt to be fed to the press and after this portion has been stretched and is ready for curing, the side bars must again be moved toward the belt to prevent the spreading of the same. This invention relates to 110

the means for moving the side bars toward and from the belt.

Each of the side bars C is connected at intervals with laterally extending bars or links 5 D by means of which the side bars are moved laterally of the apparatus. In the particular construction shown each of these connecting links D is provided with a rounded end or head portion d which is adapted to 10 fit into a correspondingly shaped aperture or recess in the outer edge of the side bar. The end or head portion d may be substantially in alignment with the connecting link D or may extend laterally therefrom as indicated at d' in order that the pressure of 15 the links acting against the side bars may be distributed at substantially equal distances along the side bars.

In order to move the connecting links laterally of the apparatus the following mechanism is preferably employed. At each side 20 of the apparatus a shaft E is arranged which extends substantially throughout the length of the apparatus and which is suitably journaled on brackets F which are preferably secured to the side of the lower platen, the brackets shown being secured to the side walls by means of bolts or machine screws f. Each of the shafts is provided with a plurality 25 of eccentrics e secured at intervals to the shaft and cooperating with eccentric straps G.

The brackets F are also provided with suitable guideways f' extending laterally 30 with reference to the apparatus and with which carriages or slides H cooperate. In the particular construction shown each of the slides H is provided with a T-shaped extension or guide portion h adapted to 35 operate with a guide-way f' of a bracket to guide the slide H laterally with reference to the apparatus. The slides H are connected with the eccentric straps G in any suitable manner, for example the eccentric straps in 40 the construction shown are provided with extensions g which are pivotally connected with the slides H. As shown in the drawings, the slides H are provided with slots h' into which the extensions g of the eccentrics 45 enter, and pivot pins h' secured on the slides and extending through the slots h' form connections between the eccentric straps and the slides.

The upper face of each slide H is preferably arranged in substantially the same 50 plane as the upper face of the lower platen and is provided with suitable means for connecting with a link D, the connection being preferably such as to permit the connecting links to be adjusted with reference to the 55 slides so that the side bar may be held in different relations to the platens for adapting the apparatus to operate on belts of different widths. In the particular construction 60 shown in the drawings this is accom-

plished by providing each slide H with an upwardly extending pin or projection I and by providing each connecting link D with a plurality of holes i into any of which the pin or projection I may enter, the holes i being so spaced on the connecting links as to hold the side bars in such relations as are desirable to operate on belts of different widths.

The relation between the eccentrics and the slides is preferably such that a half turn of the shafts E will cause the slides to move the desired distance. Any suitable means may be provided for turning the shafts, such for example as levers K, Figs. 1 and 3, 75 mounted on the shafts. The shafts are preferably turned so that when the side bars C are in their inner or belt-engaging positions, the eccentrics will be in dead center positions as shown in Fig. 8, so that pressure on the side bars will not tend to cause the shaft E to turn, thus ensuring a secure holding of the side bars in the desired positions. The side bars C may be held against movement 80 in the direction of their length by any suitable means, such as rollers c arranged at 85 the ends of the side bars and engaging an end of the lower platen.

The mechanism described for moving the side bars is simple and inexpensive in construction and thoroughly reliable in operation, and has the advantage that it can be easily applied to vulcanizing presses now in use. By means of the construction described 90 the mechanism can be very easily adjusted to enable the apparatus to operate on belts of different widths.

I claim as my invention:

1. In an apparatus for treating belting and the like, the combination of a platen 95 adapted to receive the belt, a side bar movable toward and from said belt, slides arranged at a side of said platen and connected with said side bar, and means for moving said slides to cause said side bar to move 100 toward and from a belt.

2. In an apparatus for treating belting and the like, the combination of a platen 105 adapted to receive the belt, a side bar movable toward and from said belt, slides arranged at a side of said platen and connected with said side bar, a shaft arranged 110 at a side of said platen and connections between said shaft and said slides for moving the slides laterally of said apparatus.

3. In an apparatus for treating belting and the like, the combination of a platen 115 adapted to receive the belt, a side bar movable toward and from said belt, a shaft arranged on a side of said platen, eccentrics on 120 said shaft, and connections between said eccentrics and said side bar for causing the eccentrics to move said side bars laterally of said apparatus.

4. In an apparatus for treating belting 125

- and the like, the combination of a platen adapted to receive the belt, a side bar movable toward and from said belt, slides arranged at a side of said platen and connected with said side bar, a shaft arranged at a side of said platen, eccentrics on said shaft, and connections between said eccentrics and said slides for moving the slides laterally of the apparatus.
- 10 5. In an apparatus for treating belting and the like, the combination of a platen adapted to receive the belt, a side bar movable toward and from said belt, slides arranged at a side of said platen, links connecting said slides and said side bar, and means for simultaneously moving all of said slides laterally of the apparatus.
- 15 6. In an apparatus for treating belting and the like, the combination of a platen adapted to receive the belt, a side bar movable toward and from said belt, slides arranged at a side of said platen, links forming an adjustable connection between said side bar and said slides, and means for simultaneously moving all of said slides laterally of the apparatus.
- 20 7. In an apparatus for treating belting and the like, the combination of a platen adapted to receive the belt, a side bar movable toward and from said belt, slides arranged at a side of said platen, links connected at one end to said side bar and having apertures adapted to cooperate with pins on said slides to form an adjustable connection between said side bar and said slides, and means for simultaneously moving all of said slides laterally of the apparatus.
- 25 8. In an apparatus for treating belting and the like, the combination of a platen adapted to receive the belt, a side bar movable toward and from said belt, slides arranged at a side of said platen and connected with said side bar, brackets secured to a side of said platen and having guides for said slides, and a shaft journaled on said brackets and connected with said slides to simultaneously move all of said slides laterally of the apparatus.
- 30 9. In an apparatus for treating belting and the like, the combination of a platen adapted to receive the belt, a side bar movable toward and from said belt, slides arranged at a side of said platen and connected with said side bar, brackets secured to a side of said platen and having guides for said slides, a shaft journaled on said brackets, eccentrics on said shaft, and connections between said eccentrics and said slides for moving said slides laterally of the apparatus.
- 35 10. In an apparatus for treating belting and the like, the combination of a platen adapted to receive the belt, a side bar on said platen movable to engage the side of the belt, a plurality of brackets arranged on the side of said platen, each of said brackets including a guide portion and a bearing, a shaft arranged in the bearings of said brackets, slides arranged in said guide portions, connections between said shafts and said slides for moving said slides laterally of the apparatus, and adjustable connections between said slides and said side bar.
- 40 11. In an apparatus for treating belting and the like, the combination of a platen adapted to receive the belt, a side bar on said platen movable to engage the side of the belt, a plurality of brackets arranged on the side of said platen, each of said brackets including a guide portion and a bearing, a shaft arranged in the bearings of said brackets, slides arranged in said guide portions, connections between said shafts and said slides for moving said slides laterally of the apparatus, links connected at one end with said side bar, and adjustable connections between said links and said slides for varying the position of said side bars with reference to the platen, said links serving to move said side bars transversely of the apparatus.

CHARLES H. PAEPLOW.
